EXCAVATING TOOL

Filed Sept. 24, 1942

INVENTOR

Henry K. Weinstein
By Archworth Martin
His Attorney

My invention relates to a device, and, more particularly, to an excavating tool for removing dirt from curb boxes or service boxes whose upper ends are usually flush with the sidewalk and in whose lower ends shut-off valves are located in pipe lines that lead from a gas or water main into residences and other buildings. Occasionally the covers of these boxes become displaced or loose, and dirt accumulates in the boxes to such an extent as to cover the valve stem to a considerable depth, and thus prevent access of a long-handled wrench thereto. In such cases, it has generally been necessary to make an excavation and remove the curb box, so that the gas or water can be shut off. This not only calls for considerable labor, but time is required to secure a street opening permit from the municipal authorities to do the digging. Meanwhile there may be waste and damage because of uncontrolled flow of water or gas. Thereafter the paving must be repaired.

One object of my invention is to provide a device whereby dirt may conveniently be removed from curb boxes, to permit of access to shut-off valves at the lower ends of the boxes, without the necessity of making an excavation and removing the curb boxes.

Another object of my invention is to provide an excavating tool of such form that the excavated dirt can conveniently be dislodged from the tool.

Some of the forms which my invention may take are shown in the accompanying drawing, wherein Figure 1 is a vertical sectional view of a curb box with my excavating tool therein; Fig. 2 is a vertical sectional view showing a different form of tool, and Fig. 3 is a view taken on the line III—III of Fig. 2.

Referring first to Fig. 1, a water or gas line is indicated by the numeral 4, a shut-off valve 5 being provided with a stem 6 whereby the valve can be opened and closed with the usual wrench. The curb box may be of conventional form with a base portion 7, a lower tubular section 8 and an upper tubular section 9. The parts 8 and 9 are threaded for relative longitudinal adjustment, so that the box is adapted for use with pipe lines at various depths.

The excavating tool comprises a tubular cutter member 11 that has cutting teeth 12 at its lower end. At the upper end of the tube 11, portions thereof are cut away to form legs 13 whose upper ends are welded to a coupling member 14. The coupling 14 is threaded for connection with a tubular stem 15 which may suitably be of half-inch pipe. The stem 15 may be of a length suit-

able to insure that the cutter will reach to the bottom of curb boxes of any length, and may be composed of several joints of pipe having threaded connection with one another. At its upper end, the stem 15 carries a pipe cross 16 or the like, of standard form, into which pipes or rods 17 may be threaded to serve as handles for turning the cutter.

An auger bit 19 has threaded connection with 10 the coupling 14 and is held at desired positions of vertical adjustment therein by a set screw 20. If the dirt is tightly packed in the curb box, the bit 19 may be set so that it projects a considerable distance below the cutter tube 11, as shown 15 in Fig. 1. In such cases, when the bit approaches the bottom of the box, the tool will be lifted out and the set screw loosened to permit the bit to be turned farther up into the coupling, so that the bit will not come into contact with the water 20 line in case the tool is tilted so that the bit passes the valve stem. The lower end of the tube 11 is tapered somewhat, so that it can be moved downwardly in the box without too great interference from gravel or other hard material, and will 25 not catch on the sides of the box.

In use, the tool is inserted in the box and the cutter tube 11, together with the bit 19, are rotated while the tube is being pushed downwardly. Dirt will accumulate in the tube 11 and as it 30 becomes filled, it can be lifted from the box from time to time and the dirt knocked out of it. While there may usually be some loose dirt remaining around the valve stem 6 after a dirt-removing operation, such amount of dirt will not 35 be sufficient to prevent engagement of the stem with a wrench.

In Figs. 2 and 3 I show an excavating tool similar to that of Fig. 1, but wherein provision is made for effecting discharge of dirt from the cutter tube 22 which, in this case, has only two legs or arms 23 whereby it is connected to a coupling 24. This tool contains a scraper 25 that is of inverted U form and whose legs lie close to the inner wall of the tube 22, so that when the 45 scraper is rotated, it will separate the dirt from the inner wall of the tube 22. A cap piece 26 is bolted to the scraper yoke 25 and has upstanding arms 27 that serve as handles by means of which the scraper may be rotated. The arms 27 50 on the member 26 extend radially somewhat beyond the inner surface of the cutter sleeve 22, as shown in Fig. 3, so that it will be vertically supported by the sleeve at points intermediate the arms 23. The shank of the bit 28 is notched 55 to permit of vertical adjustments thereof, it be-

ing held at its adjusted position by a thumb screw 29.

In use the tool of Fig. 2 will be operated to take up dirt in the same manner as Fig. 1. However, in those cases where the dirt is wet and sticks to the inner wall of the tube 22, upon removal of the tool from the service box, the scraper 25 will be given rotative movement to dislodge the dirt from the tube, and in case the dirt is of such tenacity that it still adheres to the auger bit, the thumb nut will be turned to release the bit and allow it, together with the adhering dirt, to drop from the tube 22. When the dirt is wet and soft, rotation of the tool may not be necessary, since by simply forcing the tool downwardly into the box may cause the tube 22 to become filled with dirt that can be dislodged therefrom upon removal of the tool from the box.

In some instances the nature of the dirt in the box will be such that it can be removed by the tubular cutter alone, without having the bit in place, since the tubular cutter can simply be dropped into the box and then withdrawn with the dirt adhering to the inner wall thereof.

I claim as my invention:

1. An excavating tool for cleaning curb boxes

and the like, comprising a tubular cutter having a cutting edge on its lower end, a stem connected to the upper end of the cutter for rotating the same, an auger bit disposed within the cutter and having connection with said stem, a scraper disposed within the cutter and extending longitudinally thereof, and means for moving the scraper to dislodge dirt from the inner wall of the cutter.

10. 2. An excavating tool for cleaning curb boxes and the like, comprising a tubular cutter having a cutting edge on its lower end and an opening through an upper portion of its side wall, a stem connected to the upper end of the cutter for rotating the same, an auger bit disposed within the cutter and having connection with said stem, a scraper disposed within the cutter and extending longitudinally thereof, and an arm on the scraper extending into the said opening, by which the scraper may be oscillated to dislodge dirt from the inner wall of the cutter, the vertical walls of the opening being spaced apart a great distance relative to the width of the arm, whereby the arm and the scraper may be given oscillatory movement about the axis of the cutter.
